UNITED STATES PATENT OFFICE.

ANTONIE K. STEUWER, OF MEMPHIS, TENNESSEE.

GARMENT HOLDER.

Application filed August 23, 1924. Serial No. 733,681.

My invention relates to garment holders.

The principal object of the invention is to provide an article of this class that will serve to hold the garment in flat, stretched condition when packed in a receptacle, particularly a suitcase or hat box, and the invention also aims to provide a holder that may be contracted or expanded to enable it to fit within receptacles of different dimensions and accommodate it to garments of various sizes.

Another object of the invention is to provide means of a simple and effective character for fixing the movable members of the holder frame in adjusted position.

Another object of the invention is the provision of means for suspending the holder from a hook which shall co-operate with the adjustability of the member in varying the external dimensions of the holder.

With these objects in view, my invention is embodied in preferable form in the device hereinafter described and illustrated in the accompanying drawings in which—

Fig. 1 is a plan view of the holder showing the same in contracted position and tied;

Fig. 2, a similar view showing it fully expanded vertically and laterally;

Fig. 3, a section on line 3—3 of Fig. 1; and

Fig. 4, a section on line 4—4 of Fig. 1.

Referring to the drawings, the holder consists of a substantially rectangular frame comprising four main members relatively movable with respect to adjoining members to provide the body which is extensible in two directions at right angles to one another, and in this frame 1, 2, 3 and 4 designate these main members, each having two arms at a right angle to one another. The arms of each member shown in the drawings as extending transversely overlap and are adapted to slide upon the transverse arms of the adjoining members. A loop guide clip 5 is fixed to the transverse arm of the frame member 1 and embraces said arm and also the transverse arm of the member 2 which is free to slide transversely through the loop guide clip and is held against and parallel with the arm of member 1 in their relative transverse sliding movements. A similar guide clip 6 is fixed to the end of the transverse arm of the member 2 and embraces, retains and slides upon the arm of member 1. Similarly the lower transverse arms of the members 3 and 4 are provided respectively with loop guide clips 7 and 8.

By means of this overlapping telescoping arrangement of the respective transverse arms of members 1 and 2, and 3 and 4 respectively, the holder may be extended or contracted laterally to conform to garments of different widths and hold the garments in properly stretched condition, or to fit receptacles of different widths.

The vertical arms of the members 1 and 3 overlap and are adapted to telescope and are provided with loop guide clips 9 and 10 respectively, at their ends. Similarly the vertical arms of the members 2 and 4 are provided with like loop guide clips 11 and 12. This arrangement of the vertical arms of the frame members permits a vertical telescoping action of members 1 and 2, with respect to members 3 and 4, to accommodate the holder to different lengths of garments or different lengths of receptacles.

At their upper ends, each of the vertical arms of the members 3 and 4 has a transverse arm, which arms overlap and form a telescoping cross bar 13 intermediate the upper and lower bars of the frame formed by the main transverse arms of the members.

Retaining and guiding loop clips 14 and 15 are secured to the ends of the overlapped arms of this bar to permit transverse relative movement of the arms as the frame is extended or contracted laterally. This intermediate cross bar not only serves as a means to strengthen and stiffen the frame of the holder but also as a support for trousers or other articles of apparel.

Secured to one of the arms of this bar 13 is a positive locking member consisting preferably of a cord or other flexible article 16 and which passes through guide eyes 17 on the arms. This flexible member is adapted to be tied to the vertical side arms of the sliding members to hold them in fixed position and against either vertical or lateral movement. Co-operating with the tying member are notches 18 formed in the edge of the vertical arm of the member 2 within which the cord may be engaged when tied to prevent displacement thereof; and, when tied in desired position passes through the notches 18 on the vertical arm member 2 to hold the members. The notches 18 on the edge of the vertical arms are brought into registration and the flexible member 16, when tied, holds the notches in registration and thereby secures the vertical arms in the desired positions.

The device is adjusted vertically and laterally to the desired size, and secured to the desired size by the tying member 16. Then the garment is put on the device in a hanging position after which, if the device is to be used in a suitcase or other packing receptacle, the parts of the garment are folded in proper relation to each other and around the device as will hold the garment in a flat unwrinkled condition.

Connected to the corners of the members 1 and 2 is a flexible suspending member 19, by means of which the holder may be hung on a hook in a closet or wardrobe trunk. Owing to the flexible character of this suspender, it co-operates with the telescoping transverse arms in permitting lateral adjustment of the holder.

It will be seen that the device described provides a holder which will be flat within a suitcase or hat box, or similar receptacle and may be adjusted, within limits, to fit said receptacle, and will thus hold the garments in flat, unwrinkled condition.

It is clear that changes in the particular

form of the parts, within the scope of the appended claims, may be made without departing from the principle of my invention.

What I claim is:

1. A garment holder comprising a series of members each having angularly disposed arms, the arms of adjoining members that extend in the same direction being overlapping and slidable upon one another and retaining and guiding members carried by said arms.

2. A garment holder having top and bottom transversely telescoping bars and side longitudinally telescoping side bars, and a transversely telescoping bar intermediate the top and bottom bars and movable with parts of the side bars.

3. A garment holder having top and bottom telescoping bars and side telescoping bars, an intermediate telescoping cross bar, and a flexible tying member secured to said cross bar.

In testimony whereof I affix my signature.

ANTONIE K. STEUWER.
